UNITED STATES PATENT OFFICE.

EDWARD A. SCHREIBER, OF CHICAGO, ILLINOIS, ASSIGNOR TO EGBERT H. GOLD, OF CHICAGO, ILLINOIS.

TICKET-HOLDER.

1,241,564.

Specification of Letters Patent.

Patented Oct. 2, 1917.

Application filed March 27, 1916. Serial No. 86,922.

To all whom it may concern:

Be it known that I, EDWARD A. SCHREIBER, a citizen of the United States, residing at Chicago, in the county of Cook and State 5 of Illinois, have invented certain new and useful Improvements in Ticket-Holders, of which the following is a specification.

My invention relates to a ticket or train check holding device to be attached to the 10 wall, window, curtain or other part of a railway car; and the object of the invention is to provide a simple device which can be cheaply manufactured and will be sightly in appearance, for holding a plurality of 15 tickets or checks so that they may be readily seen by the conductor in passing through the car.

The invention is illustrated, in certain preferred embodiments, in the accompanying 20 drawings wherein—

Figure 1 is a fragmentary elevation of the side wall of a railway car showing the ticket holder, constructed in accordance with my invention, fastened to the wall 25 panel between the windows.

Fig. 2 is an enlarged view of the ticket holder.

Fig. 3 is a section on line 3—3 of Fig. 2.

Figs. 4 and 5 are views, in elevation and 30 section, of a modification, Fig. 5 being a section on line 5—5 of Fig. 4.

Figs. 6 and 7 are views corresponding to Figs. 4 and 5, respectively, showing another modification.

Figs. 8 and 9 are similar views showing 35 a different form of the invention.

Figs. 10 and 11 are similar views showing still another modification, and

Figs. 12 and 13 are views, in elevation 40 and section respectively, showing another form.

Like characters of reference designate like parts in the several figures of the drawings.

In Figs. 1, 2 and 3 the device consists of 45 a single piece of wire bent so as to form two loops 25 which lie flatwise against the wall panel 26 except at their outer extremities which are preferably bent up slightly, 50 as indicated at 27. The wire between the loops is formed with an arcuate bend 28 and on the opposite side the extremities of the wire 29, 30 are similarly bent. 31 is a washer which lies over the parts of the wire 55 just described, and 32 a screw which fastens

the device to the panel. It will be observed that the wire does not cross itself at any point. All parts of the wire lie in the same plane except the outwardly bent portions at the extremities of the loops. 60

The device shown in Figs. 4 and 5 consists also of a single wire which does not cross itself at any point, the wire being bent so as to form three loops 33, 34, 35, one within the other. The ends of the wire 65 are bent to form eyelets 36 through which extend the attaching screws 37. This device will accommodate three tickets held one above the other so as to be all in plain sight.

In Figs. 6 and 7 there are two tickets 70 holding loops 38, 39, and outside of these an attaching loop 40 secured at top and bottom to the panel by screws or other fastening devices 41.

The device shown in Figs. 8 and 9 has 75 three ticket holding loops 42, 43, 44, one within the other. One end of the wire, the device consisting of a single wire which no where crosses itself, is formed with an eyelet 45 for the attaching screw 46. The lower 80 end of the device, including the free extremity 47 of the wire, is covered by plate 48.

The device shown in Figs. 10 and 11 is 85 similar to that shown in the first two figures but with double the number of loops. The wire is bent to form four radial loops 49. The inner ends of the loops are held firmly against the panel by washer 50 and screw 51.

The device shown in Figs. 12 and 13 consists of two wires, one bent to form relatively long loops 52, and the other forming shorter loops 53. The second mentioned device is placed on top of the first one, preferably with the interposition of a washer 54. Both devices are secured to the panel 90 by a screw 55, the head of which bears against a washer 56. The wire forming loops 53 will take the position shown by the full lines, or it may be turned around to the dotted line position. 95

I claim:

1. A ticket holder for a railway car consisting of a wire bent to form a plurality of spring ticket holding loops, said loops lying for most of their length flatwise 105 against the side of the car to which the device is attached with their extremities arranged a trifle from the same.

2. A ticket holder for a railway car consisting of a single wire, which does not cross 110

itself at any point, bent to form four radially arranged loops, and attaching means which engages the wire at the central point between said loops, and attaching means for securing the wire to a part of the car at a point between said loops.

3. A ticket holder for a railway car consisting of a wire bent to form a plurality of spring loops for supporting tickets between said loops and the part of the car to which the device is attached, and attaching means for engaging the wire at a central point between the loops and for holding said

loops in ticket-holding position against the said part of the car to which the device is attached.

4. A ticket holder for a railway car, consisting of a single wire which does not cross itself at any point and is bent to form two diametrically opposed loops which lie flat against the part of the car to which the device is attached, and attaching means engaging the wire at a point between said loops to hold the same in ticket-supporting position against the car.

EDWARD A. SCHREIBER.

Copies of this patent may be obtained for five cents each, by addressing the "Commissioner of Patents. Washington, D. C."
